UNITED STATES PATENT OFFICE

2,654,428

MULTIPLE NOTCHING DIE

Anton Martincic, Chicago, Ill.

Application October 19, 1949, Serial No. 122,258

16 Claims. (Cl. 164—31)

1
The invention relates generally to punching or shearing dies and, more particularly, to a multiple die for performing any one of a plurality of operations.

The invention has among its objects the production of a novel die assembly which is constructed to perform a plurality of different shearing operations, which is simple in construction, very efficient and durable in operation, and relatively inexpensive to manufacture, and which is of particular use in small shops whereby a single machine may be employed for a number of different operations.

Another object of the invention is the production of such a die provided with novel means for guiding and gauging the material upon which the operations are to be performed.

A further object of the invention is the production of such a die structure in which certain of the die members may be interchanged to provide additional versatility in the single die structure.

Many other objects and advantages of the construction herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters indicate like or corresponding parts;

Fig. 1 is a top plan view of the female die member;

Fig. 2 is a sectional view taken approximately on the line 2—2 of Fig. 1 of the female die member, with the co-operating male punch member shown in elevation;

Fig. 3 is a perspective view of the female die member;

Fig. 4 is a bottom plan view of the male punch member;

Fig. 5 is a perspective view of one of the material guide members illustrated in Figs. 1 and 2;

Fig. 6 is a plan view of a corner portion of a piece of sheet material illustrating one operation which may be performed by the die shown;

Fig. 7 is a plan view of a corner portion of a piece of sheet material illustrating a second operation which may be performed by the die shown;

Fig. 8 is a plan view of a corner portion of a piece of sheet material illustrating a third operation which may be performed by the die shown; and

2
Fig. 9 is a plan view of an end of strip material illustrating a fourth operation which may be performed by the die shown.

Referring to the drawings, and particularly to Figs. 1 and 2, 1 indicates generally the female die member comprising a base member 2 of generally rectangular shape having the corner portions notched, as indicated at 3, to provide mounting flanges 4 at each corner of the device adapted to be engaged by suitable clamping elements whereby the member 2 may be rigidly mounted on the bed of the machine on which it is to be employed. The upper face 5 of the member 2 is provided with a more or less rectangular-shaped recess 6 in which are positioned a plurality of die blocks 7a, 7b, 7c, and 7d, the blocks each being positioned adjacent a respective corner of the recess 6 and spaced from one another, as clearly illustrated in Figs. 1 and 3, and rigidly secured to the base 2 by suitable bolts 8 passing through each block and threaded into the base member 2. Positioned between each adjacent pair of blocks and likewise seated in the recess 6 is a spacer block 9 on which are mounted respective guide supporting members 11, the latter and the blocks 9 each being rigidly maintained in position by bolts 12 passing through the base member 2, respective blocks 9, and threaded into each bar 11, as clearly illustrated in Fig. 2. It will be noted that as the upper surfaces of the blocks 9 are inset below the upper surfaces of the adjacent blocks, each bar 11 is positioned in a channel between adjacent blocks 7, whereby each bar is rigidly held in position with respect to the base member and the die blocks.

As clearly illustrated in Figs. 1 and 3, the die block 7a is provided with a diagonally extending shearing edge 13, the block 7b with L-shaped cutting edges 14, the block 7c with a curved cutting edge 15, and the block 7d with the curved cutting edge 17. The blocks 7a and 7b are also provided with additional curved cutting edges 18 and 19, respectively, for the purposes herein-after set forth. The base member 2 is provided with a centrally located opening 21 therethrough to permit passage of sheared material through the die.

Co-operable with the die member 2 is a male punch member, indicated generally by the numeral 22, adapted to be mounted on the movable drive member or ram 23 of the punch press by means of the large bolt 24 and pins 25. As illustrated in Fig. 4, the member 22 is generally X-shaped, having a plurality of radially extending

portions 26, with cutting edges 27a, 27b, 27c, and 27d being positioned between adjacent projections 26. Each of the latter is provided with a downwardly extending flange 28 adapted to be positioned adjacent the blocks 9, and it will be noted that as the blocks 9 and adjacent ends of the bars 11 are outwardly offset with respect to the adjoining side edges of adjacent die blocks 7, channels between each pair of die blocks are formed, the channels being of a size to receive the adjacent ends of each projection 26 and provide a guide therefor whereby the female die member 2 and male member 22 are maintained in accurate alignment at all times. It might be mentioned that while Fig. 2 illustrates the male and female members as being completely separated, such separation is merely for the purpose of clearly illustrating the parts, and normally the upward movement of the male member would be limited to such an extent that the flanges 28 do not leave their respective guide channels during normal operation of the device.

Mounted on the member 22 is a pair of blocks 29a and 29b, the block 29a being rigidly secured to the member 22 by a suitable screw 31, and the block 29b being secured to the member 22 by a suitable screw 32, with the head of each screw being inset into its respective block, as clearly illustrated in Fig. 4. The block 29a is provided with a shearing edge 33' complementary to the shearing edge 13 of the block 7a, and the block 29b is provided with a pair of shearing edges 34 complementary to the shearing edges 14 of the block 7b. In like manner, the shearing edge 27a of the member 22 is complementary to the edge 18 of the block 7a, and the shearing edge 27b is complementary to the shearing edge 19 of the block 7b.

It will be apparent that in the operation of the device, the edges 13 and 33' will diagonally cut a piece of material placed upon the block 7a and extending over the edge 13. Likewise, material placed on the block 7b will be notched along the cutting edges 14, and in like manner, material placed upon the blocks 7c or 7d will be cut on pre-determined radii, the radius of the edge 17, as illustrated, being less than that of the edge 15.

The block 7a may be removed from the base member 2 by loosening the pair of screws 8 associated therewith, following which the block may be rotated through 180° to position the cutting edge 18 in operative position relative to the male member 22, after which the screws 8 may be screwed down to rigidly secure the block in such position. When it is desired to utilize the cutting edge 18, the block 29a is disconnected from the male member 22 by removing the screw 31 and with it the block, thereby exposing the cutting edge 27a which is complementary to the cutting edge 18. In like manner, the block 7b may be reversed to position the cutting edge 19 in operative position, in which case the block 29b is removed from the male member, exposing the cutting edge 27b, which is complementary to the cutting edge 19. Thus by use of the cutting edges 15, 17, 18, and 19, stock may be cut on any one of four different radii, and by positioning the blocks 7a and 7b, as illustrated in Figs. 1 and 3, stock may also be cut on the diagonal or provided with a right angle notch therein.

Fig. 6 illustrates the corner portion of a piece of stock A after it has been cut by the edges 13 and 33' to produce a diagonal corner edge "a," and Fig. 7 illustrates a corner portion of a piece

of material B after it has been cut by the edges 14 and 34 to form a notch "b." In like manner, Fig. 8 illustrates a portion of a sheet C, the corner of which has been rounded by means of the cutting edges 15 and 27c; and Fig. 9 illustrates the rounding of an end of a strip D by means of the cutting edges 17 and 21d.

To facilitate guiding and gauging of material being cut, guide members 35 and 35' are provided. As illustrated in Fig. 5, each guide member 35 is generally triangular in shape and is provided along one edge with a downwardly extending flange 36, the bottom face of each member being provided with a rib 37, extending transversely to the flange 36 and adapted to be positioned in one of the channels 38 in the guide bars 11 adjacent the blocks 7a and 7b. Each of the members 35 is provided with an elongated slot 39 extending through the rib 37 and adapted to receive a mounting screw 41 threaded into the bar 11. Assuming stock is to be cut, as illustrated in Fig. 6, with the cutting edges 13 and 33', the guide members 35 would be mounted on the supporting bars 11 adjacent the block 7a, as illustrated in Fig. 1, and as the guide members may be shifted transversely with respect to their supporting bars 11, the amount of material removed from the corner during the cutting operation may be readily varied by moving the guide members 35 relative to their bars. The ribs 37 and channels 38 insure proper alignment of the guide flanges 36, at all times maintaining the flanges on the respective guide members at a 90° relationship in any of their adjusted positions.

The guide members 35' are adapted for use in guiding strip material into any of the co-operating cutting edges and, as illustrated in Fig. 1, are set up to guide material, such as the strip D illustrated in Fig. 9, relative to the cutting edges 17 and 21d. Each of the guide members 35' is provided with a flange 42 adapted to seat upon the upper surface of the respective bars 11, each flange being provided with an elongated slot 43 extending parallel to its respective bar adapted to receive a mounting screw 44 threaded into the bar 11. As illustrated in Fig. 1, each bar 11 is provided with two threaded bores 45 adapted to receive screws 44 whereby the guide members 35' may be mounted on either side of the respective bars in operative position with respect to any one of the die blocks 7. Each of the guide members 35' is provided with an edge 46 extending diagonally relative to the bar 11 supporting the same, at an angle of substantially 45° with respect thereto. The diagonal edges 46 on the respective guide members extend in opposite directions relative to their mounting edges to form right and left hand guide members, so that when the members are mounted as illustrated in Fig. 1, the pair of edges 46 thereof will extend parallel to one another and parallel to a line passing through the axis of the punch member and the center of radius of the curved edge 17 of the die block 7d. It will be apparent that by sliding the guide members along their respective bars 11, the distance between the edges 46 may be varied, as well as the distance between each edge and the radial line above referred to, at the same time maintaining the parallel relation of the edges 46, whereby strip material of different sizes may be readily and accurately guided into the die.

In the embodiment of the invention illustrated, the bar 11 between die blocks 7c and 7d is not provided with a channel 38 as are the remaining bars, as the blocks 7c and 7d are not reversible. Consequently, the curved cutting edges

15 and 17 would be normally employed either for trimming the ends of strip material, such as illustrated in Fig. 9, or for rounding the corners of a sheet of material, such as illustrated in Fig. 8. In the event strip material is employed, the guide members 35' may be employed in connection with either of the die blocks, and if corners are to be trimmed, such as illustrated in Fig. 8, the adjacent bars 11 provide guide means for the sheet to be cut, and it is merely necessary to butt the two intersecting edges of the sheet material against the adjacent vertical edges of the bars

11. As a result, it is unnecessary to employ the guides 35 with either of the blocks 1c or 1d. However, the guide members 35' may be of use in connection with any one of the die blocks and regardless of the positions of the blocks 1a and 1b; in view of which all of the bars 11 are provided with threaded bores 45 for mounting the guide members 35' thereon. While the die blocks 7 have been illustrated with various shaped cutting edges, it is believed apparent that the shape of such edges, as well as the combination of edges employed, may be varied to suit particular requirements.

It will be noted from the above description that I have provided a novel die structure for performing a plurality of different cutting operations, together with novel means for guiding material into the same, which device is relatively simple in construction, durable, and very efficient in operation.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a punching die, the combination of a female die member and a co-operable male punch member moveable relative to each other on a pre-determined axis, co-operating means on the die and punch members for maintaining the same in axial alignment during relative movement therebetween, a plurality of die blocks radially arranged about said axis, said punch member having a portion for each block complementary to and co-operable with a portion of the latter, one of said blocks being constructed to be selectively positioned relative to the base member whereby a second portion of such block may be positioned to co-operate with said punch member, a block adapted to be removably secured to the punch member and having a portion complementary to and co-operable with the second portion of said die block when the latter portion is in operable position, radially extending guide supporting bars carried by said die member, each bar being positioned between adjacent die blocks, and a pair of guide members, each mounted on one of an adjacent pair of said bars and adjustable relative to the die block therebetween for guiding material relative to the co-operating portions of such die block and punch member.

2. In a punching die, the combination of a female die member including spacer blocks and a co-operable male punch member moveable relative to each other on a pre-determined axis, co-operating means on the die and punch members for maintaining the same in axial alignment during relative movement therebetween, a die block

mounted on said female member, said punch member having a portion complementary to and co-operable with a portion of said block, a pair of radially extending guide supporting bars mounted upon said spacer blocks affixed to said die member and extending at right angles to one another, each bar being positioned at one side of said block, and a pair of guide members, each mounted on one of said bars and adjustable relative to the latter for guiding material relative to the co-operating portions of such die block and punch member.

3. In a punching die, the combination of a female die member including spacer blocks and a co-operable male punch member moveable relative to each other on a pre-determined axis, co-operating means on the die and punch members for maintaining the same in axial alignment during relative movement therebetween, a die block mounted on said female member, said punch member having a portion complementary to and co-operable with a portion of said block, a pair of radially extending guide supporting bars mounted upon said spacer blocks affixed to said die member and extending at right angles to one another, each bar being positioned at one side of said block, and a pair of guide members, each mounted on one of said bars, said guide members having material engageable guide edges extending parallel to one another and at an angle of 45° to their respective supporting bars and adjustable relative to the latter in a direction parallel thereto for guiding material relative to the co-operating portions of such die block and punch member.

4. In a punching die, the combination of a female die member including spacer blocks arranged at right angles to each other and a co-operable male punch member moveable relative to each other on a pre-determined axis, co-operating means on the die and punch members for maintaining the same in axial alignment during relative movement therebetween, a die block mounted on said female member, said punch member having a portion complementary to and co-operable with a portion of said block, a pair of radially extending guide supporting bars affixed to said spacer blocks mounted upon said die member and extending at right angles to one another, each bar being positioned at one side of said block, and a pair of guide members, each mounted on one of said bars, said guide members having material engageable guide edges extending parallel to their respective supporting bars and adjustable relative to the latter in a direction at right angles thereto for guiding material relative to the co-operating portion of such die block and punch member.

5. In a punch die, the combination of a female die member and a co-operable male punch member moveable relative to each other on a pre-determined axis, co-operating means on the die and punch members for maintaining the same in axial alignment during relative movement therebetween, a plurality of die blocks radially arranged about said axis, said punch member having a portion for each block complementary to and co-operable with a portion of the latter, one of said blocks being constructed to be selectively positioned relative to the base member whereby a second portion of such block may be positioned to co-operate with said punch member, and a block adapted to be removably secured to the punch member and having a portion complementary to and co-operable with the second portion of said die block when the latter portion is in operable position, radially extending guide supporting bars carried by said die member, each bar being positioned between adjacent die blocks, and a pair of guide members, each mounted on one of an adjacent pair of said bars and adjustable relative to the die block therebetween for guiding material relative to the co-operating portions of such die block and punch member.

portion of said die block when the latter portion is in operable position.

6. In a punching die, the combination of a female die member and a co-operable male punch member moveable relative to each other on a pre-determined axis, co-operating means on the die and punch members for maintaining the same in axial alignment during relative movement therebetween, a die block mounted on said female member, said punch member having a portion complementary to and co-operable with a portion of said block, the latter being constructed to be selectively positioned relative to the base member whereby a second portion of such block may be positioned to co-operate with said punch member, a block adapted to be removably secured to the punch member and having a portion complementary to and co-operable with the second portion of said die block when the latter portion is in operable position, a pair of radially extending guide supporting bars carried by said die member and extending at right angles to one another, each bar being positioned at one side of said block and a pair of guide members, each mounted on one of said bars, said guide members having material engageable guide edges extending parallel to their respective supporting bars and adjustable relative to the latter in a direction at right angles thereto for guiding material relative to the co-operating portion of such die block and punch member.

7. In a punching die, the combination of a female die member and a co-operable male punch member moveable relative to each other on a pre-determined axis, co-operating means on the die and punch members for maintaining the same in axial alignment during relative movement therebetween, a die block mounted on said female member, said punch member having a portion complementary to and co-operable with a portion of said block, the latter being constructed to be selectively positioned relative to the base member whereby a second portion of such block may be positioned to co-operate with said punch member, a block adapted to be removably secured to the punch member and having a portion complementary to and co-operable with the second portion of said die block when the latter portion is in operable position, a pair of radially extending guide supporting bars carried by said die member and extending at right angles to one another, each bar being positioned at one side of said block, and a pair of guide members, each mounted on one of said bars, said guide members having material engageable guide edges extending parallel to one another and at an angle of 45° to their respective supporting bars and adjustable relative to the latter in a direction parallel thereto for guiding material relative to the co-operating portions of such die block and punch member.

8. In a punch die, the combination of a female die member and a co-operable male punch member moveable relative to each other on a pre-determined axis, co-operating means on the die and punch members for maintaining the same in axial alignment during relative movement therebetween, a plurality of die blocks radially arranged about said axis, said punch member having a portion for each block complementary to and co-operable with a portion of the latter, at least one of said blocks being constructed to be selectively positioned relative to the base member whereby a second portion of such block may be positioned to co-operate with said punch

member, at least one block adapted to be removably secured to the punch member and having a portion complementary to and co-operable with the second portion of said die block when the latter portion is in operable position, radially extending guide supporting bars carried by said die member, each bar being positioned between adjacent die blocks, and a pair of guide members, each mounted on one of an adjacent pair of said bars and adjustable relative to the die block therebetween for guiding material relative to the co-operating portions of such die block and punch member.

9. In a punch die, the combination of a female die member and a co-operable male punch member moveable relative to each other on a pre-determined axis, said female die member having a recess in its upper face, a plurality of die blocks positioned in said recess and radially arranged about said axis, a spacer member positioned in said recess between each adjacent pair of die blocks, said punch member having a portion for each block complementary to and co-operable with a portion of the latter, a guide projection on said punch member co-operable with each adjacent pair of die blocks and the spacer member therebetween for maintaining the female die member and punch member in axial alignment during relative movement therebetween, radially extending guide supporting bars carried by said spacer members, each bar being positioned between adjacent die blocks and extending radially with respect to said axis, and a pair of guide members, each mounted on one of an adjacent pair of said bars and adjustable relative to the die block therebetween for guiding material relative to the co-operating portions of such die block and punch member.

10. In a punch die, the combination of a female die member and a co-operable male punch member moveable relative to each other on a pre-determined axis, said female die member having a recess in its upper face, a plurality of die blocks positioned in said recess and radially arranged about said axis, a spacer member positioned in said recess between each adjacent pair of die blocks, said punch member having a portion for each block complementary to and co-operable with a portion of the latter, a guide projection on said punch member co-operable with each adjacent pair of die blocks and the spacer member therebetween for maintaining the female die member and punch member in axial alignment during relative movement therebetween, one of said blocks being constructed to be selectively positioned relative to the base member whereby a second portion of such block may be positioned to co-operate with said punch member, a block adapted to be removably secured to the punch member and having a portion complementary to and co-operable with the second portion of said die block when the latter portion is in operable position, radially extending guide supporting bars carried by said spacer members, each bar being positioned between adjacent die blocks and extending radially with respect to said axis, and a pair of guide members, each mounted on one of an adjacent pair of said bars and adjustable relative to the die block therebetween for guiding material relative to the co-operating portions of such die block and punch member.

11. In a punch die, the combination of a female die member and a co-operable male punch member moveable relative to each other on a pre-

terminated axis, a plurality of die blocks radially arranged about said axis, said punch member having a portion for each block complementary to and co-operable with a portion of the latter, at least one of said blocks being constructed to be selectively positioned relative to the base member whereby a second portion of such block may be positioned to co-operate with said punch member, and at least one block adapted to be removably secured to the punch member and having a portion complementary to and co-operable with a second portion of said die block when the latter portion is in operable position.

12. In a punch die, the combination of a female die member and a co-operable male punch member movable relative to each other on a predetermined axis, co-operating means on the die and punch members for maintaining the same in axial alignment during relative movement therebetween, a die block mounted on said female member, said punch member having a portion complementary to and co-operable with a portion of said die block, the latter being constructed to be selectively positioned relative to the base member whereby at least one other portion of such die block may be positioned to co-operate with said punch member, at least one block adapted to be removably secured to the punch member and having a portion complementary to and co-operable with at least one other portion of said die block when said other portion is in operable position.

13. In a punch die, the combination of a female die member and co-operable male punch member movable relative to each other on a predetermined axis, a die block mounted on said female member, said punch member having a portion complementary to and co-operating with a portion of said die block, the latter being constructed to be selectively positioned relative to the base member whereby at least one other portion of such die block may be positioned to co-operate with said punch member, at least one block adapted to be removably secured to the punch member and having a portion complementary to and co-operable with at least one other portion of said die block when said other portion is in operable position.

14. In a punching die, the combination of a female die member including spacer blocks and a co-operable male punch member movable relative to each other on a predetermined axis, a die

block mounted on said female member, said punch member having a portion complementary to and co-operable with a portion of said block, a pair of radially extending guide supporting bars affixed to said spacer blocks and extending at right angles to one another, each bar being positioned at one side of said block, and a pair of guide members, each mounted on one of said bars and adjustable relative to the latter for guiding material relative to the co-operating portions of such die block and punch member.

15. In a punch die, the combination of a female die member and a co-operating male punch member movable relative to each other on a predetermined axis, said female die member being adapted to receive at least one selectively positionable die block having differently shaped working edge portions, and said male punch member including projections at right angles to each other and adapted to receive at least one removable block between contiguous projections for forming said male punch member into a configuration complementary to the co-operable working edge portions of the female die member.

16. In a punch die, the combination of a female die member including spacer blocks mounted on the die member on axes at right angles to each other and a co-operable male punch member movable relative to each other on a predetermined axis, said female die member being adapted to receive a plurality of positionable die blocks between and contiguous to the spacer block, each having differently shaped working edge portions, and said male punch member including projections at right angles to each other and adapted to receive a plurality of removable blocks between contiguous projections for forming said male punch member into a configuration complementary to the co-operable working edge portions of the female die member.

ANTON MARTINCIC.
